United States Patent Office

Des. 200,866
Patented Apr. 13, 1965

200,866

LANDSCRAPER

Charles Buford Coss, Neodesha, Kans., assignor to Independent Manufacturing Co., Inc., Neodesha, Kans., a corporation of Kansas

Filed June 15, 1964, Ser. No. 80,409

Term of patent 14 years

(Cl. D39—1)

Fig. 1.

Fig. 2.

Fig. 3.

Fig. 4.

Fig. 5.

Fig. 6.

Fig. 7.

FIG. 1 is a perspective view of the landscaper, showing my new design;

FIG. 2 is a rear elevational view thereof;

FIG. 3 is an elevational view of one end thereof;

FIG. 4 is a top plan view thereof;

FIG. 5 is a front elevational view thereof;

FIG. 6 is an elevational view of the end thereof opposite to that shown in FIG. 3; and

FIG. 7 is a sectional view taken on line 7-7 of FIG. 5 of the landscaper.

I claim:

The ornamental design for a landscaper, as shown.
